UNITED STATES PATENT OFFICE.

J. L. QUINBY, OF PLEASANT GROVE, PENNSYLVANIA.

IMPROVED STONE-GATHERER.

Specification forming part of Letters Patent No. 47,566, dated May 2, 1865; antedated April 26, 1865.

To all whom it may concern:

Be it known that I, JOSIAH L. QUINBY, of Pleasant Grove, in the county of Lancaster and State of Pennsylvania, have invented a new and Improved Machine for Gathering Stones; and I do hereby declare that the following is a full, clear, and exact description of the same, reference being had to the accompanying drawings, making a part of this specification, in which—

Figure 1 is a side sectional view of my invention, taken in the line *xx*, Fig. 2; Fig. 2, a plan or top view of the same; Fig. 3, a view of a portion of the back of the receiving-box pertaining to the same.

Similar letters of reference indicate corresponding parts in the several figures.

This invention relates to a new and improved machine for gathering stones from a field and depositing them in a proper receptacle from which they may be readily discharged at the will of the driver.

The invention consists in the employment or use of a revolving toothed cylinder and an endless apron, said parts being arranged, operated, and applied to a mounted frame, as hereinafter described and used, in connection with a stone-receiving box suspended in the mounted frame, and provided with a hinged tail-board and hinged bottom having a peculiar fastening, which may be operated by the driver from his seat to admit of the stone being discharged at any desired point or place.

To enable those skilled in the art to fully understand and construct my invention, I will proceed to describe it.

A represents a rectangular frame, which is mounted on two wheels, *B B'*, the latter being at the back part of the frame and placed loosely on a fixed axle, *C*. The wheel *B* has a toothed wheel, *D*, attached concentrically to it at its inner side.

E is a shaft, which is placed transversely on the frame *A* just in front of the axle *C*, and has a pinion, *F*, at one end of it. The bearing *a* of this shaft, which is near the pinion *F*, is a sliding one, and it is connected by a rod, *b*, with a lever, *c*, which is underneath a platform, *d*, on the frame *A*, and works on a fulcrum-pin, *e*. The inner end of the lever *c* is connected by a rod, *f*, with a lever, *G*, which

is attached to a shaft, *H*, underneath the platform *d*, the lever extending up through a slot, *g*, in the platform. By drawing the lever *G* backward the bearing *a* of the shaft *E* will be moved forward and the pinion *F* thrown out of gear with the wheel *D*, and by shoving said lever forward the pinion *F* will be thrown in gear with the wheel *D*. The lever *G* is retained in a forward and backward position by catches *h h*, arranged in any proper way.

I I represent two parallel bars, the back ends of which are attached by pivot-bolts *i* to the frame *A*, one at each side of it. Between the front parts of these bars *I I* there is fitted a shaft, *J*, which is allowed to turn freely, and on this shaft *J* and the shaft *E* there is fitted an endless apron, *K*, formed of two chains, *j j*, with transverse slats *k* attached to them, the slats being provided with teeth *l*. Between the front parts of the bars *I I*, directly in front of the shaft *J*, there is a scoop, *L*.

M M are two bars or arms, the back ends of which are attached to the frame *A* by the same pivot-bolts, *i*, which attach the bars *I* to the frame *A*. Between the front ends of the bars or arms *M M* there is fitted a cylinder, *N*, having its periphery provided with teeth *m*. At each end of the cylinder *N* there is a pulley, *n*, around which cross cords or belts *n** pass, said cords or belts also passing around pulleys *o o* at the ends of the shaft *E*.

The shaft *H*, to which the lever *G* is attached, has a pulley, or part pulley, *p*, at each end of it, and the bars *I I* and arms *M M* are connected to the pulleys or part pulleys *p p* by means of cords *q*.

From the above description it will be seen that as the machine is drawn along the endless apron *K* will be moved in the direction indicated by the arrow 1, while the toothed cylinder *N* will be rotated in the direction indicated by the arrow 2, and with a quicker speed than it would have if it received its motion by contact with the earth. The scoop *L* rests upon the ground, while the teeth of the cylinder *N* act upon the ground and loosen the stones embodied in it, so that the scoop *L* will raise them upon the lower end of the apron *K*, which conveys them into a box or receiver, *O*, at the back part of the frame *A*.

At any time when it is desired to render the

machine inoperative the driver from his seat P draws back the lever G, and thereby throws the pinion F out of gear with the wheel D, and at the same time causes the scoop L and cylinder N to be raised free from the ground.

The box or stone-receiver O is provided with a tail-board, Q, the hinges *r* of which are at its upper edge. The bottom *s* of the box or receiver is connected at its front edge to the bottom of the front side of the box or receiver by hinges *t*, (see Fig. 1,) and the bottom *s* and tail-board Q are held in a proper closed state by clasps R R, the lower ends of which are connected by hinges or joints *u* to the back edge of the bottom *s*. The clasps R are each slotted near their upper ends to allow short arms *v v*, which are connected by joints *w w* to the tail-board, to pass through, and these arms *v* are secured or held in an upright position to the tail-board by means of a shaft, S, attached to the tail-board, said shaft having its parts which fit over the arms *v* bent in crank form, as shown at *a'*. (See Fig. 3.) This shaft S also has an arm, *b'*, to which a cord, *c'*, is at-

tached, which leads to the driver's seat P, and the driver at any time, when desired, by pulling the cord *c'*, may turn the shaft S, and thereby release the arms *v v* and clasps R R, so that the bottom *s* will drop and the tail-board Q left free to swing out and the stone allowed to drop or pass out from the box or receiver O.

Having thus described my invention, what I claim as new, and desire to secure by Letters Patent, is—

1. The endless apron K, in connection with the rotating toothed cylinder N and the scoop L, arranged with the bars I I and arms M M, applied to the mounted frame A, substantially as and for the purpose herein set forth.

2. The shaft H, the bars I I, arms M M, and cords *q*, in combination with the lever *d*, bearing *a*, shaft E, and lever G, all arranged substantially as shown.

JOSIAH L. QUINBY.
